REAR VIEW MIRROR

Edward R. Lee, Ceresco, Mich., assignor to S. H. Leggitt
Company, Marshall, Mich., a corporation of Michigan

Filed Apr. 14, 1965, Ser. No. 84,781

Term of patent 14 years

(Cl. D14—6)

FIGURE 1 is a perspective view of a rear view mirror, showing my new design;

FIGURE 2 is a rear elevational view thereof;

FIGURE 3 is a front elevational view thereof;

FIGURE 4 is a side elevational view thereof;

FIGURE 5 is a top view of FIGURES 1 and 7;

FIGURE 6 is a bottom view of FIGURES 1 and 7; and

FIGURE 7 is a rear elevational view of a rear view mirror, showing another embodiment of my design wherein the mirror support arm is articulated.

The portions of the vehicle shown in broken lines in FIGURE 1 are included for illustrative purposes only.

I claim:

The ornamental design for a rear view mirror, as shown and described.
